UNITED STATES PATENT OFFICE.

EDWARD M. TUCKER, OF OAKESDALE, WASHINGTON.

BAG-HOLDER.

1,167,604.

Specification of Letters Patent. Patented Jan. 11, 1916.

Application filed May 10, 1915. Serial No. 27,083.

To all whom it may concern:

Be it known that I, EDWARD M. TUCKER, a citizen of the United States, residing at Oakesdale, in the county of Whitman and State of Washington, have invented certain new and useful Improvements in Bag-Holders, of which the following is a specification.

This invention relates to improvements in bag holding devices and has to do more particularly with devices for holding bags of the larger type such as the fabric bags which are used for bagging grain.

It is one of the objects of my invention to provide a device which will not only support the bag with the open end held spread for receiving the contents, but also to provide such a device whereby the same may be "jigged" up and down so as effectively to fill the lower corners.

A further object of the invention is to provide a device which is pivotally supported, when in one adjustment and which is fixedly supported when in another adjustment, the device being provided with means for effectively grasping and holding the open end of the bag in a spread position irrespective as to whether or not the device is fixedly supported or in a position to be "jigged" about the axis of its pivotal support.

Other features and objects of the invention will be more fully described in connection with the accompanying drawings.

In the drawings:—Figure 1 is a view in front elevation of a bag holding device embodying one form of my invention. Fig. 2 is a view in side elevation of the bag holding structure showing the same in the position which it would assume if a bag were about to be attached thereto, Fig. 3 is a plan view of the holding structure with the parts in the position shown in Fig. 2, Fig. 4 is a view in side elevation with the holding structure adjusted to be tilted about its pivotal axis and illustrating the parts adjusted to support a bag thereon, Fig. 5 is a view of a portion of a supporting frame or jack, Fig. 6 is an enlarged detail view of a latch member.

Like characters of reference designate similar parts throughout the different figures of the drawings.

A filling spout is designated at 1 and the filling ends or terminals are forked, as indicated at 2, for the purpose of simultaneously discharging into two bags, the latter being indicated at 3. A strap 4 is secured to the spout 1, as at 5, and the ends of the strap are secured at 6 to a supporting bar 7, the latter extending behind the forked portions 2, of the spout 1. Hanger straps 8 depend from the supporting bar 7 to form the pivotal support for the bag holding device, as will later appear. "Jigger" or detachable supporting means is provided for the bag holding device and the same comprises "jigger" members 9 which are fixed to the forked ends 2, as indicated at 10. The fixed "jigger" members are provided with offset central portions 11 terminating in ends 12 provided with slots 13. The end 14 of each slot functions as a supporting shoulder.

The foregoing parts may be broadly designated as the spout structure.

Because of the weight imposed by the filled bags which are suspended from the spout structure, I provide a frame or jack support for the spout structure which is herein illustrated as of the following construction: Said frame includes uprights 15, adapted to rest upon the floor or other supporting surface, and extending up for detachable connection with supporting bar 7. The uprights 15 have upper ends 16 which engage the bottom of the bar 7, to support the same, and said uprights 15 are provided with hooks 17 which extend over the bar 7 to hold the frame in supporting relation therewith. The frame is suitably braced by transverse and diagonally disposed members 18 and 19 and may be detached from the bar 7 by being swung backwardly until the shoulders 16 are released from engagement with the bottom of bar 7.

It will be understood that the device of my invention may be incorporated in a single spout structure just as well as in the double or forked spout form and while I have herein shown, and will now describe two bag holding devices, reference will be made to only one thereof as both are identical in construction and operation.

Referring more particularly to Figs. 2 to 4, 20 designates the side bars of the holding frames, the side bars 20 being forked exten-

sions of a handle bar 21. The bars 20 are spaced apart slightly, near their juncture with handle bar 21, as indicated at 22. Between said space portions is pivoted at 23, a 5 "jigger" locking or supporting bar 24 which extends up through the slot 13 and which is provided with a pin 25 to prevent the jigger or locking bar 24 from being withdrawn downwardly through slot 13 and out of slide- 10 able connection with the fixed member 9. A locking lug 26 is formed on said bar 24 for engagement with shoulder 14 to support or lock the frame in the position shown in Fig. 2. However, slot 13 is sufficiently elongated 15 to permit bar 24 to be shifted into the position shown in Fig. 4 for up and down movement of the frame to "jig" the supported bag 3 when the operator manually oscillates handle bar 21. Bar 24 is provided with suitable thumb or finger grips 27 and 28 to facilitate shifting the bar 24 on its pivot 23 without necessitating release of the hand of the operator from handle bar 21.

The forked terminals of extensions or side bars 20, are bored as at 29, for passage therethrough of a pivot rod 30 which is mounted in hangers 8. It will now be seen that the bag holding device has a pivotal mounting, at one end thereof, and a "jigger" connection at the other end thereof whereby the bag holding device may either be oscillated about its pivot mounting or held supported and in a fixed position.

A suitable brace 31 is provided to stiffen 35 the bag holding frame and in the bars 20 are journaled for free rotative movement, two rocking hook bars or rods 32 and 33. I preferably provide the bars 20 with hanger straps 34 and 35 in which the rods 32 and 40 33 are directly journaled so as to dispose said rods somewhat below the frame bars 20. Bag hooks 36 and 37 are mounted on said rods 32 and 33, on one side of the frame, and on the other side, I mount hooks 38 and 39. 45 Hooks 38 and 39 are provided with actuating shanks 40 and 41, as will be seen more clearly by reference to Fig. 2. An operating bar 42 is pivoted at 43 on a bearing strap 44 which extends upwardly above the side 50 bar 20 to which it is attached so as to dispose the pivot 43 above the axes of rods 32 and 33. An operating link 45 is pivoted at 46 to said operating bar and is pivoted at 47 to the shaft 40 of hook 38. An operating link 48 is pivoted at 49 to operating bar 42, on that side of pivot 43, opposite the pivot 46, and said link 48 is pivoted to shank 41 at 55 50. Operating bar 42 is offset at 51 so that its handle end 52 will engage the top of one 60 of the side bars when in the locking position shown in Fig. 4, to arrest movement of the operating bar beyond a locking position. A weighted end 53 is provided for the operating bar to resist movement of the latter 65 from a locking position. It is only neces-

sary to move the operating bar 42 in a clockwise direction to the position shown in Fig. 2, in order to dispose the bag hooks in a position for attaching a bag thereto, and I therefore provide a stop 54 on one of the 70 bars 20, to limit movement of bar 42 beyond the position shown in Fig. 2.

The parts are arranged or adjusted in the position shown in Fig. 2 for the purpose of extending the open end of the bag about the 75 bag hooks. Then the operating lever 42 is shifted into the position shown in Fig. 4 to force the bag hooks outwardly and secure the bag in suspended relation with respect to the holding frame. After the bag has been 80 partially or wholly filled, the operator may grasp the handle bar 21, raising the frame slightly thereby releasing engagement between lug 26 and shoulder 14 so that by depressing the thumb upon projection 27, the 85 bar 24 will assume the position shown in Fig. 4. While the bag is securely held by the hook, the handle bar 21 may be slightly oscillated up and down about pivot bar or rod 30 to "jig" the bag sufficiently to cause 90 the contents to completely fill all the lower portions. Thereafter, the carrying frame may be raised and by extending the forefinger of the hand under grip 28, the bar 24 may be oscillated or swung forwardly to dispose lug 26 in supported relation with shoulder 14. 95

By reference to Fig. 4, it will be seen that line xx intersects centers 29, 47, 43 and 50, and that center 49 is above the line and 100 center 46 is below the line. It will thus be seen that the dead center or off dead center positions of the pivots is such that when the operating lever 42 is in the position shown in Fig. 4, the stress thereon, together with 105 the weight 53, will tend to hold the lever in the position shown in Fig. 4.

It is believed that the novelty and utility of my invention will be clearly understood from the foregoing description, and while I 110 have herein shown and described one specific form of my invention I do not wish to be limited thereto except for such limitations as the claims may import.

I claim:—

1. In a bag holding mechanism, a spout structure, bag holding means pivoted on said structure and having a handle end, a jigger member mounted on said spout structure and having a slotted end provided with a shoulder, and a jigger bar pivoted on said handle end and projecting through said slotted end and having a lug for coaction with said shoulder to support said holding means in a fixed position, substantially as described. 120

2. In a bag holding mechanism, a spout structure provided with a pivot bar, bag holding means pivoted on said bar, and devices mounted on said means and on said spout structure for coaction to release said 130

holding means or to support the latter, substantially as described.

3. In a bag holding mechanism, a supporting structure including a spout, bag holding means pivoted on said structure, and devices mounted on said means and on said structure for co-action to release said holding means for movement about its pivot or

to support said means in a fixed position on said structure, substantially as described. 10

In testimony whereof I affix my signature in presence of two witnesses.

EDWARD M. TUCKER.
